UNITED STATES PATENT OFFICE.

LOTHAR VON KÖPPEN, OF POTSDAM, GERMANY.

BLADE FOR SKATES, SLEIGHS, SKEES, AND THE LIKE.

1,088,709.

Specification of Letters Patent.

Patented Mar. 3, 1914.

Application filed March 29, 1912. Serial No. 687,160.

To all whom it may concern:

Be it known that I, LOTHAR VON KÖPPEN, capitalist, a citizen of the German Empire, residing at Potsdam, in the Kingdom of 5 Prussia, Germany, have invented certain new and useful Improvements in Blades for Skates, Sleighs, Skees, and the like, of which the following is a specification.

The present invention relates to improvements in ice skates and similar sliding devices having a curved runner or runners.

The object of the improvements is to make the runner of such an articular curve that, first, each of its several articles or sections 15 corresponds in form with the natural movement of the skate when in use; that is to say, with the line, curve or figure to be described by that section of the runner which becomes active during such work, as it has been 20 learned by experience that in straight-away skating, curving or describing figures but quite determined sections of the runner will come into operative engagement with the ice surface; that, second, the foot of the skater 25 is given a more secure stand; and that, third, the skate is safer for inexperienced persons and children.

With these ends in view, my invention consists in certain novel features of construction and combinations of parts, as is 30 hereinafter fully described and pointed out in the claims.

In the accompanying sheet of drawings— Figures 1 and 2 are bottom views of a pair 35 of skates made in accordance with my invention, Fig. 1 showing the right foot skate and Fig. 2, the left foot skate; Fig. 3 is a lateral longitudinal elevation of a somewhat modified form of my improved skate; Figs. 40 4 and 5 are similar bottom views as Figs. 1 and 2 illustrating the modification shown in Fig. 3.

Similar letters refer to similar parts through the several views.

45 Referring to the construction shown in Figs. 1 and 2, the runner or blade *c* (the ice-engaging surface of which may be of any appropriate cross sectional form and is curved upwardly at the front and at the

rear in the usual manner) is bodily convexed inwardly at its forward part *c*¹, so that its forward extremity *g* curves outwardly, and convexed outwardly at its rear part *c*², so that its rear extremity *h* curves inwardly, so that the runner *c* shall have a 55 double curve. It is advisable to let the front and rear extremities of the runner or blade terminate in a plane with the median line of the base of the skate.

In the modification shown in Figs. 3 to 5, 60 the body of the runner has a straight middle portion *b*, an outwardly-convexed forward part *b*¹ and an inwardly-convexed rear part *b*², the latter preferably tapering toward its rear extremity *h*. The latter as well as the 65 front extremity *g* terminate in a plane with the median line of the base of the skate and the straight middle portion *b* of the runner lies in said median line.

When the turned up front edge of the 70 runner is provided with a roughened shoulder *s*, a so-called saw—as is the case in figure-cutting skates—this part or saw is preferably brought again back into the median line of the skate.

Having now particularly described and ascertained the nature of my said invention and in what manner the same is to be performed, I declare that what I claim is:—

1. An ice skate having the ice-engaging 80 surface of its blade curved upwardly at the front and at the rear, said blade being bodily convexed inwardly at its forward part, so that its forward extremity curves outwardly, and its rear part convexed outwardly so that 85 its rear extremity curves inwardly.

2. An ice skate having the ice-engaging 90 surface of its blade curved upwardly at the front and at the rear, said blade being bodily convexed inwardly at its forward part, so that its forward extremity curves outwardly, and its rear part convexed outwardly so that 95 its rear extremity curves inwardly, said front and rear extremities of the blade terminating in a plane with the medium line of the base of the skate.

3. An ice skate having the ice-engaging surface of its blade curved upwardly at the

front and at the rear, said blade being bodily convexed inwardly at its forward part, so that its forward extremity curves outwardly, and its rear part convexed outwardly so that its rear extremity curves inwardly, the middle portions of the body of each runner being straight and lying in the median line of the base of the skate.

In testimony whereof I hereunto affix my signature in presence of two witnesses.

LOTHAR VON KÖPPEN.
